UNITED STATES PATENT OFFICE.

DAVID F. STAMBAUGH, OF ST. LOUIS, MISSOURI

BED-BOTTOM.

SPECIFICATION forming part of Letters Patent No. 327,611, dated October 6, 1885.

Application filed August 21, 1884. Serial No. 141,143. (No model.)

To all whom it may concern:

Be it known that I, DAVID F. STAMBAUGH, a citizen of the United States, residing at St. Louis, in the county of St. Louis and State of Missouri, have invented certain new and useful Improvements in Bed-Bottoms, of which the following is a specification, reference being had therein to the accompanying drawing.

10 My invention relates to certain improvements in spring bed-bottoms, and is designed, objectively, to produce a device that shall accommodate itself easily and quickly to every motion of the occupant, at the same time being simple, strong, and not liable to get out of order.

In describing the device reference is had to the annexed drawing, representing a partial plan view of the bed-bottom.

20 A designates the sides of a frame, having end pieces, B, preferably set at a slight angle to the horizontal, and cross-pieces C, connecting the said sides. At each end of the frame, secured to the pieces B, are a series of spiral 25 springs, D, respectively sustaining the ends of the web of chains E, which are each composed of a series of links. These links are U-shaped, and have the bend or base indented, as shown at F, so that the links, 30 when all secured together, will preserve their form, which tends toward the rectangular, giving thereby a large bearing-surface. Between each two spirals D are links G, which are connected to the end pieces, B, and are 35 loosely secured to the end links of the chains, so that the said spirals may have a restricted play, but not sufficient to distort or strain them.

The cross-pieces C each support a series of 40 springs, H, on the tops of which rest the chains E, the said springs being connected to

each other and to the chains by short links I. The chains of the web are held normally equidistant from each other by spirals K, which extend entirely across the said web. These 45 cross-spirals allow the chains to yield readily to pressure and return them to their normal position as soon as the pressure is relieved.

Near each end of the side pieces, A, and fastened thereto, are spiral springs L, also 50 connected to one of the springs H. These springs prevent any material side movement of the springs H, and thereby obviate any danger of their mashing over on one side.

It is evident that the bed-bottom will yield 55 to pressure from any direction, and therefore be very comfortable to an occupant. The chains receive a mattress without pressing into it, and support it perfectly. The links, though shown as rectangular or U-shaped, may be of 60 other forms. The complete device is simple, lighter than slats, and cheaply and easily constructed.

Having described the device, what I claim is—

65 A spring bed-bottom consisting of a frame having cross-pieces supporting spiral springs, a web of flat-linked chains connected to the frame by spring-coils having a restricted play, the said chains resting on the spiral springs 70 and connected one to the other by transverse coils, and coils connecting the spiral springs to the frame, the several parts being connected and operating substantially as and for the purpose specified.

In testimony whereof I affix my signature in presence of two witnesses.

DAVID F. STAMBAUGH.
